CLAIM

The ornamental design for portion of a dispenser, as shown and described.

DESCRIPTION

FIG. 1 is a top perspective view of my portion of a dispenser design;

FIG. 2 is a bottom perspective view thereof;

FIG. 3 is a front view thereof;

FIG. 4 is a right side view, the left side being a mirror image;

FIG. 5 is a rear view thereof;

FIG. 6 is a top view thereof; and,

FIG. 7 is a bottom view thereof.

The broken lines in the drawings are for illustrative purposes only, and form no part of the claimed design.
